UNITED STATES PATENT OFFICE

153,291

DESIGN FOR AN AIRPLANE

Alexander Kartveli, Huntington Station, N. Y.,
assignor to Republic Aviation Corporation,
Farmingdale, N. Y., a corporation of Delaware

Application October 31, 1946, Serial No. 134,420

Term of patent 14 years

(Cl. D71—1)

To all whom it may concern:

Be it known that Alexander Kartveli, a citizen of the United States and a resident of Huntington Station, in the county of Suffolk and the State of New York, has invented a certain new, original, and ornamental Design for an Airplane, described and claimed in the following specification and shown in the accompanying drawings wherein:

Fig. 1 is a plan view of an airplane embodying the present design;

Fig. 2 is a side elevation thereof with the landing gear protracted;

Fig. 3 is a front elevation thereof with the landing gear retracted; and

Fig. 4 is a perspective view from the front with the landing gear retracted.

What is claimed is:

The ornamental design for an airplane, substantially as shown.

ALEXANDER KARTVELI.
